United States Patent

Des. 237,868
Patented Dec. 2, 1975

237,868

DRAFTING INSTRUMENT

Peter S. Hoagland, 18769 Saratoga,
Lathrup Village, Mich. 48076

Original design application Dec. 15, 1971, Ser. No. 208,511, now Patent No. 232,051, which is a continuation-in-part of design application Ser. No. 160,234, July 6, 1971, now Patent No. 226,226. Divided and this application Jan. 2, 1974, Ser. No. 429,848

Term of patent 14 years

Int. Cl. D10—04

U.S. Cl. D10—62

FIG. 2.

FIG. 1 is a top left perspective view of a drafting instrument, showing my new design, the bottom being generally plain;

FIG. 2 is a right side elevational view thereof.

This is a divisional application of Ser. No. 208,511, filed Dec. 15, 1971, now design patent Des. 232,051 which is in turn a continuation-in-part of Ser. No. 160,234, filed July 6, 1971, now design patent Des. 226,226.

I claim:

The ornamental design for a drafting instrument, as shown and described.
